FACIAL MASK

Geraldine M. Fisher, 87 Kenwood Road,
Grosse Pointe Farms, Mich.

Filed May 11, 1959, Ser. No. 55,854

Term of patent 14 years

(Cl. D86—10)

The broken line illustration of the wearer in Figure 1 is merely for the purpose of showing the environmental use of the mask.

I claim:

The ornamental design for a facial mask, substantially as shown and described.
